TOY MACHINE GUN

Robert C. Flynt and Ursal K. Butler,
Winston-Salem, N. C.

Application September 28, 1942, Serial No. 460,012

3 Claims. (Cl. 46—192)

This invention relates to toy machine guns.

An object of the invention is to provide, in a single construction, a toy gun which can easily be adapted for selective use as a breast or sub-machine gun, or as a stand supported gun.

Another object is to provide a toy machine gun constructed of non-metallic or "non-critical" parts and which nevertheless is strong and durable.

Another object is to provide a toy machine gun of the character referred to in which the parts may be economically manufactured and assembled.

A further object is to provide a toy gun of the character stated including a new and improved noise making device adapted to give forth a staccato "clop" like sound resembling the report of an actual cartridge firing gun more nearly than prior noise making devices.

Other objects will become apparent from a reading of the following detailed description, the appended claims, and the accompanying drawings, in which:

Figure 1 is a side elevation showing a toy machine gun embodying the invention, conditioned or set up to simulate a stand or tripod supported machine gun;

Figure 2 is a top plan view of the toy gun set up as shown in Figure 1;

Figure 3 is a section on the line 3—3 of Figure 1;

Figure 4 is a central vertical longitudinal sectional view of the toy machine gun conditioned to simulate a breast or sub-machine gun;

Figure 5 is a fragmentary side elevation showing details of a noise making device;

Figure 6 is a vertical section on the line 6—6 of Figure 4; and

Figure 7 is a detail perspective view showing parts of a noise making device separated.

An illustrative embodiment of the invention is represented by a toy machine gun generally designated A, the butt or stock end being indicated at B and the muzzle end at C. Structurally the toy gun includes an elongated unitary wooden body member 1 extending from the butt end B to the muzzle end C, and being of rectangular cross section throughout its length with the exception of the extreme muzzle end portion, which is formed with a round portion 2 offset laterally from the longitudinal axis of the member 1. The round part 2 is formed to simulate the muzzle end of a gun barrel. At its opposite end a transverse breast piece 3 is secured to the elongated member 1

by any suitable means, such as a dowel pin 3a.

A plate or disc like member 4 formed of wood to simulate a magazine, is slotted so as to fit over and be attached to the body 1 intermediate the ends thereof in a plane perpendicular to the longitudinal axis of the body 1.

A cooling barrel or cylinder is simulated by a tubular member 5 fitting over and surrounding the body 1 and extending from the magazine-simulating member 4 almost to the muzzle end of the member 1. Holes 6 in the tubular member 5 add to the simulation of an actual machine gun cooling barrel or cylinder. The tubular member 5 has contact substantially throughout its length with the bottom face of the longitudinal member 1. Inasmuch as the bottom face of the member 1 is flat, the inner wall of the member 5 will contact the member 1 along the two side edges of the bottom face of the member 1. The tubular member 5, being formed of resilient material such as cardboard or papier-mâché, may be secured to the member 1 by means of small fastening devices, such as nails 7 so as to form a durable non-rattling joint. As shown in Figures 4 and 6 the nails crimp or press the flexible material of the tube 5 inwardly against the bottom of the member 1. If there should be a tendency for the joint between the parts 5 and 1 to loosen up after long use, the resiliency of the connection provided by the nails 7 and cardboard end portions of the tubular member 5 will take up the slack or looseness and a strong non-rattling joint will be maintained for a long time.

35 A noise making device generally designated 8 adapted to make sound simulating the discharge of explosive charges is mounted on the body member 1 to the rear of the magazine simulating member 4. Preferably the body 1 is formed with a portion 9 of reduced cross sectional area providing a recess 10 which is bridged by a wooden sounding block 11 extending beyond the front and rear ends of the recess 10 and projecting laterally beyond or overlapping the sides of the body 1. Nails 12 extending through the block 11 into the body 1 at opposite ends of the recess 10 hold the block in place so that the block will reinforce the weakened or reduced section 9 of the body 1.

One rear corner portion of the block 11 is cut away so as to provide a side surface 13 on the block lying in the same plane as a side surface 14 on the body 1. The cut-out corner referred to overlaps the recess 10. A clapper 15 is mounted within the recess 10 so as to lie normally

against the underside of the block 11. Nails 16 are provided for securing the forward end of the clapper 15 against the block 11, the rear end of the clapper 15 being free so that the clapper may be flexed downwardly and then released to permit it to return and strike the sounding block 11. The sounding block preferably is formed with a hole 17 and in accordance with the invention, the clapper 15 is formed of resilient non-metallic material, preferably "Bakelite." We have found that a clapper formed of such non-metallic material cooperates with the sounding block having a hole formed therein, so as to produce a "clop" like noise resembling or simulating the sound of a discharged cartridge, much more than the noise produced by metallic clappers. Metallic clappers have been found to produce more of a "twang."

An actuator generally designated 18 is provided for depressing and releasing the clapper 15 in quick succession so as to produce a series of blows on the block 11 and to thus simulate the rapid firing of a machine gun. In the form shown, the actuator 18 comprises a square wooden rotor block journaled by a screw 19 adjacent the co-planar faces 13 and 14 of the block 11 and body 1. A pin 20 provides a handle by which the rotor may be turned. The rotor is so positioned that its corner points 21 will engage serially with the portion of the clapper 15 overlapping the cut-out corner portion of the block 11.

By mounting the clapper 15 within the recess 10 too great a flexing with consequent danger of breaking the clapper is prevented. The arrangement is such that should a child manually depress the clapper without turning the rotor 18, the clapper flexing will be limited by the reduced section 9 of the body and no damage can be done to the clapper. The clapper is covered by the block 11 except for the small clapper portion overlapping the cut-out corner of the block 11 so that it is difficult for a child to operate the clapper other than by turning the actuator 18. Another advantage of this construction is that a child is not likely to get its finger pinched between the clapper and the sounding block.

It will be observed that the sounding block 11 and the tubular member 5 abut respectively against the rear and front faces of the magazine simulating member 4, thereby bracing it and holding it against tilting.

A feature of the invention resides in providing a construction such that the gun may easily be adapted selectively for use as a submachine gun or as a stand supported gun. For this purpose a wooden hand grip piece 22 is provided with a pin 23 adapted to be received by either of two attaching stations, one comprising a hole 24 in the body 1 at a point near the longitudinal center of the body and the other comprising a hole 25 in the body adjacent the butt end of the latter. To condition the gun for use simulating a sub-machine gun, the end grip piece 22 is mounted at the forward attaching station 24. In operation, the breast piece 3 is held against the user's body, and the hand grip 22 is held in one hand, the other hand being free to operate the actuator 18.

To adapt or set up the gun to simulate a stand supported gun, the hand grip piece 22 is mounted at the attaching station 25 so as to cooperate with wooden legs 26 mounted at other attaching stations 27 to form a tripod. The attaching stations 27 may comprise holes or seats formed in the magazine simulating member 4, the arrangement being such that when the legs 26 are in-

serted in the attaching stations, the legs will diverge downwardly and outwardly from each other. When the piece 22 and legs 26 are attached to the gun to form a tripod, the gun may be set up in inclined position as shown in Figures 1, 2, and 3.

It will be observed that the parts of which the toy gun disclosed herein is made are all very simple to manufacture and their correlation is such that they may be assembled economically. The only parts formed of metal are the nails 1, 12 and 16 and the screw 19. The clapper 15 is formed of Bakelite or like material and the tubular member 5 is formed of paper, cardboard, or similar material. All of the other parts are formed of wood. Thus the gun may be constructed of readily available and so-called "non-critical" materials.

The toy gun disclosed herewith embodies the invention in a preferred form, but it will be understood that changes may be made without departing for the invention as defined in the claims.

We claim:

1. In a toy machine gun, an elongated gun body member rectangular in cross section and being formed intermediate its ends with a portion of reduced cross sectional area, and a resultant recess; and a sounding device comprising a sounding block bridging said recess and projecting laterally beyond one side of said body and longitudinally beyond both ends of said recess, means securing said block to said body member at opposite ends of said recess to thereby reinforce said portion of reduced cross sectional area, a corner portion of the laterally overlapping part of said block being cut away so that a side surface of the block will be coplanar with a side surface of said body adjacent one end of said recess, a clapper mounted in said recess, means for securing said clapper to said block adjacent the end of the recess opposite that end which is cut away at the corner, the free end of said clapper overlapping said cut away corner, and an actuator mounted to rotate against said co-planar body and block side surfaces and having points adapted to serially depress and release the clapper.

2. In a noise making toy, a body member formed with a recess; and a sounding device comprising a sounding block bridging said recess and projecting laterally beyond one side of said body member and longitudinally beyond both ends of said recess, means securing said block to said body member at opposite ends of said recess, a corner portion of the laterally overlapping part of said block being cut away so that a side surface of the block will be coplanar with a side surface of the body member adjacent one end of said recess, a clapper mounted in said recess, means for securing said clapper to said block adjacent the end of the recess opposite that end which is cut away at the corner, the free end of said clapper overlapping said cut away corner, and an actuator mounted to rotate against said co-planar body member and block side surfaces and having points adapted to serially depress and release the clapper.

3. In a toy machine gun, an elongated unitary member extending from the butt or stock end to the muzzle end and being formed at the muzzle end with a laterally offset round portion simulating a gun barrel muzzle; a member simulating a magazine mounted on said unitary

member intermediate the ends thereof; and a tubular member simulating a cooling cylinder mounted on and surrounding said unitary member from the muzzle end thereof inwardly towards said magazine-simulating member, said tubular member having contact substantially throughout its length with said unitary member, and the lateral offset of said round portions being such that said round portion is substantially centered with respect to said tubular member, the unitary member being flat along

5 the face against which the tubular member is mounted, there being fastening means extending through the tubular member and into the unitary member at said flat face thereof, and said tubular member being formed of material which is slightly yieldable whereby a strong, non-rattling joint is provided between said unitary member and said tubular member.
